UNITED STATES PATENT OFFICE

ANDRÉ GARBARINI, OF COURBEVOIE, FRANCE, ASSIGNOR, BY MESNE ASSIGNMENTS, TO LIBBEY CATAPHOTE CORPORATION, OF TOLEDO, OHIO, A CORPORATION OF OHIO

AUTOCOLLIMATING REFLECTOR

Application filed July 7, 1930, Serial No. 466,233, and in France October 17, 1929.

Autocollimating devices having a considerable covering range, of the order of 180° , and which are formed by two spherical portions, generally of different radii, contacting 5 along a diametral plane, are old in the art. These devices labour under the disadvantage of being considerably bulky, so that it is impossible to assemble a large number of units in a given space determined by the dimension 10 of the signal to be displayed. As the most favourable ratio between the diameters of the collimating lens and of the object lens is 2 to 1, it follows that in every direction the distance between axes is at least equal to D , D 15 being the diameter of the large collimating lens.

Now, as far as, for example, signals for motor cars are concerned, since these vehicles only move in a horizontal plane, only the 20 horizontal field is of interest.

The present invention which is based on this consideration, consists in eliminating the vertical field by cutting the collimating lens along two parallel planes the distance 25 between which is variable and practically equal to the diameter of the small object lens, whereby the density of the units forming the signal, and consequently, the luminosity, may be doubled without in any way modifying 30 the useful characteristics of these units.

Figs. 1, 2 and 3 of the accompanying drawing illustrate by way of example in front elevation, end elevation and plan respectively, an embodiment of an autocollimating unit 35 in accordance with the invention.

Fig. 4 is a front elevation of an embodiment of a signal made up of units of the type illustrated in Figs. 1 and 2.

Fig. 5 is an elevation of the signal in section along the line IV—IV Fig. 4.

Fig. 6 is a sectional plan view along VI—VI Fig. 4.

Fig. 7 is a plan view of a signal in the form of a portion of a cylinder and having an angular range greater than 180° .

Fig. 8 illustrates a hemispherical signal in front elevation.

Fig. 9 is an elevation in section along the line VIII—VIII, Fig. 8.

As may be seen in this drawing, (Figs. 50 1-3) an autocollimating unit according to the invention comprises a small hemispherical object lens 1, contacting along a diametral plane with a collimating lens 2 in the form of a hemisphere truncated by the 55 parallel planes P_1 , P_2 which may for example be practically tangent to the hemisphere 1. The radius of the lens 2 will be preferably double that of the lens 1.

The back 2^a of said lens 2 is faced in a 60 known manner with a coating of silver and a coating of varnish.

To form a signal 3 for motor vehicles (Figs. 4 to 6), the units are placed in vertical rows in such manner that the cutting planes 65 of the lenses 2 run horizontally, the block being cast. The useless vertical field is thus eliminated. As illustrated in Figs. 4 to 6, the units are preferably placed in staggered relation. The bulk is thus reduced and the 70 reflecting surface between the object lenses 1 is utilized to the best advantage.

The units in accordance with the invention adapt themselves to the formation of a signal 4 (Fig. 7) having a covering range greater 75 than 180° and in which the surface of the system instead of being planar is a portion of a cylinder. The units may likewise be grouped to form "ronos" signals 5 (Figs. 8 and 9) in which the surface from which the 80 object lenses project is a spherical cap.

It will be readily understood that for other applications it might be useful to eliminate the horizontal field in which case the signal 85 would be simply turned through 90° .

I claim:

1. A signal formed by a plurality of autocollimating sights each comprising in combination a hemispherical objective lens, a larger hemispherical reflector joined to said 90

- objective and truncated by two parallel planes between which said objective lies, the ratio of the radii of said lenses being a function of the refractive index of the glass of which said lenses are made, while the distance between the centers of said lenses, which are coaxial, is proportional to the desired divergence of the reflected light, the reflector lens of each unit being in contiguity with adjacent reflectors along the aforementioned cutting planes. 5
2. A signal formed by a plurality of autocollimating sights formed in a single casting and each comprising in combination, a hemispherical objective lens, a larger hemispherical reflector joined to said objective and truncated by two parallel planes between which said objective lies, the ratio of the radii of said lenses being a function of the refractive index of the glass of which said lenses are made, while the distance between the centers of said lenses, which are coaxial, is proportional to the desired divergence of the reflected light, the reflector lens of each unit being in contiguity with adjacent reflectors along the aforementioned parallel cutting planes. 10
3. A signal formed by a plurality of autocollimating sights formed in a single casting and each comprising, in combination, a hemispherical objective lens, a larger hemispherical reflector joined to said objective and truncated by two parallel planes between which said objective lies, the ratio of the radii of said lenses being a function of the refractive index of the glass of which said lenses are made, while the distance between the centers of said lenses, which are coaxial, is proportional to the desired divergence of the reflected light, the reflector lens of each unit being in contiguity with adjacent reflectors along the aforementioned parallel cutting planes. 15
4. A signal composed of a plurality of autocollimating sights formed in staggered relation in a single casting and each comprising, in combination, a hemispherical objective lens, a larger hemispherical reflector joined to said objective and truncated by two parallel planes between which said objective lies, the ratio of the radii of said lenses being a function of the refractive index of the glass of which said lenses are made, while the distance between the centers of said lenses, which are coaxial, is proportional to the desired divergence of the reflected light, the reflector lens of each unit being in contiguity with adjacent reflectors along the aforementioned parallel cutting planes. 20
5. A signal formed by a plurality of autocollimating sights formed in a single casting and each comprising, in combination, a hemispherical objective lens, a larger hemispherical reflector joined to said objective and truncated by two parallel planes between which said objective lies, the ratio of the radii of said lenses being a function of the refractive index of the glass of which said lenses are made, while the distance between the centers of said lenses, which are coaxial, is proportional to the desired divergence of the reflected light, the reflector lens of each unit being in contiguity with adjacent reflectors along the aforementioned parallel cutting planes. 25
6. A signal formed by a plurality of autocollimating sights each comprising, in combination, a hemispherical objective lens, a larger hemispherical reflector joined to said objective and truncated by two parallel planes between which said objective lies, the reflector lens of each unit being in contiguity with adjacent reflectors along the aforementioned parallel cutting planes. 30
7. A signal formed by a plurality of autocollimating sights formed in a single casting and each comprising, in combination, a hemispherical objective lens, a larger hemispherical reflector joined to said objective and truncated by two parallel planes between which said objective lies, and a coating of shining metal on the outer face of said reflector remote from said objective, the reflector lens of each unit being in contiguity with adjacent reflectors along the aforementioned parallel cutting planes. 35
8. A signal composed of a plurality of autocollimating sights formed in staggered relation in a single casting and each comprising, in combination, a hemispherical objective lens, a larger hemispherical reflector joined to said objective and truncated by two parallel planes between which said objective lies, the reflector lens of each unit being in contiguity with adjacent reflectors along the aforementioned parallel cutting planes. 40
9. A signal formed by a plurality of autocollimating sights formed in a single casting and each comprising, in combination, a hemispherical objective lens, a larger hemispherical reflector joined to said objective and truncated by two parallel planes between which said objective lies, the reflector lens of each unit being in contiguity with adjacent reflectors along the aforementioned parallel cutting planes. 45
10. A signal formed by a plurality of autocollimating sights each comprising in combination a hemispherical objective lens, a larger hemispherical reflector joined to said objective and truncated by two parallel planes between which said objective lies, the reflector lens of each unit being in contiguity with adjacent reflectors along the aforementioned cutting planes. 50
11. A signal formed by a plurality of autocollimating sights each comprising a convex

objective lens through which incident and reflected light is transmitted, a concave reflector in axial alignment therewith and truncated by two parallel planes between which the objective lies, the diameter of the reflector on a line parallel with said planes being greater than the diameter of the objective lens, and the objective lenses being arranged in spaced rows extended transversely of said planes.
